UNITED STATES PATENT OFFICE.

ALBERT B. DICK, OF CHICAGO, ILLINOIS, ASSIGNOR TO A. B. DICK COMPANY, OF CHICAGO, ILLINOIS, A CORPORATION OF ILLINOIS.

STENCIL-PRINTING MACHINE.

No. 866,718.

Specification of Letters Patent.

Patented Sept. 24, 1907.

Application filed January 5, 1904. Serial No. 187,833.

To all whom it may concern:

Be it known that I, ALBERT B. DICK, a citizen of the United States, residing at Chicago, in the county of Cook and State of Illinois, have invented a certain new 5 and useful Improvement in Stencil-Printing Machines, of which the following is a specification.

The invention concerns particularly that type of stencil-duplicating machines in which is employed a drum suitably supported and provided with mechanism for imparting thereto a rotary or oscillating movement. Such drums commonly comprise heads 10 pivotally mounted in a supporting frame and provided with a stencil-carrier of foraminated material. Over said stencil-carrier it has been common to place a pad, 15 this being held in position by means of end bars or rods, the ends whereof are dropped into notches or recesses, formed in said heads. At either end said pad is commonly stretched over a bar extending between and connecting said heads, so as to place such pad under 20 the necessary tension to cause said rods to retain their place in said notches or recesses. Over said pad the stencil is placed, suitable means being employed for securing one or both of the ends thereof in position 25 against the tendency, due to the rotation of the drum, to displacement. As an example of such means, I refer to the use of a bar extending between and connecting the heads of the drum and provided with projections over which the forward end of the stencil is placed.

The present invention concerns particularly means 30 for securing the forward end of the stencil in place upon the drum. I have found that such forward end may be held firmly in position against the strain above referred to, by means of a device movably carried, preferably by the drum heads, and capable of being readily 35 thrown to operative position to hold the stencil or to inoperative position to remove it. In the present embodiment of the invention, this device is arranged to coact with the pad-holding rods above referred to, and comprises a bail having ends turned at an angle to the 40 body portion thereof, said ends being pivoted upon the inner surfaces of the drum heads. Said body portion lies parallel, and coacts, with the rods by means whereof the pad is secured upon the stencil-carrying 45 portion of the drum. Where the material of such pad is wrapped around such drum, the fastening device here referred to is additionally advantageous, since the pressure upon the stencil is a yielding one, rather than a rigid one.

The invention is illustrated in the accompanying 50 drawing, in which

Figure 1 is a side elevation of a portion of a stencil-printing machine with my invention applied thereto, and Fig. 2 is a top plan view thereof.

Referring to this drawing, in which similar letters

denote corresponding parts, A, B designate the drum 55 heads, here shown as pivotally mounted upon a frame, which not forming part of the present invention will not be described in detail. Extending between these heads is the stencil-carrier C of foraminated material. If desired, the forward edge of said carrier may terminate in a bar extending between the drum heads A, B, although this is not essential, as will presently be seen. Such a bar, D, is here shown, but reference thereto as a bar is not to be construed as excluding the use of the forward edge of the carrier itself for the same purpose. 60

E designates the inking pad. Preferably, although not necessarily, this is formed of an endless band of felt, flannel or other textile material, and is provided with two rods F having enlarged heads f, f. In securing this pad in position, one of said rods is dropped into 70 its coacting notches in the drum heads A, B, the pad is then pulled taut, and the rod at the other end thereof dropped into its coacting notches in the drum heads A, B, distant from those just referred to. This places said pad under the necessary strain to maintain it in position. 75

G designates the stencil-clamping device, here shown as comprising the main or body portion g having angular rearwardly-turned ends g' pivoted at g² upon the inner surfaces of the drum heads A, B. The forward 80 edge of said clamping device is provided with a down-turned lip g³, which, when the clamp is in operative position to secure the forward edge of the stencil upon the drum, coacts, in the present instance, with the forward rod F, whereby the pad E is secured upon the 85 stencil-carrier C.

In applying the stencil, the same is laid over the pad E, its forward edge being down-turned over the forward rod F. The clamp G is then pressed toward its operative position, in which the down-turned lip g³, coacting 90 with the forward pad-holding rod F, will firmly bind the forward edge of the stencil in position and hold the same against the tendency, due to the rotation of the drum, to loosen said stencil and displace it.

I here observe that the clamping device above described may, if desired, be used in connection with or in addition to other stencil-holding devices adapted, for instance, to coact with stencils of a certain sort only. Thus, I have indicated on Fig. 1 of the drawing a bar extending between the heads A, B of the drum, and 100 provided upon its upper surface with studs or projections adapted to extend through perforations in the forward edge of the stencil. Where the machine is provided with such securing means (or, in fact, with any other, so far as I am aware), the device above referred 105 to may be applied forward of the same, as indicated in the drawing, so that a stencil may be secured in position regardless of whether the same be specially adapt-

ed for coaction with the particular securing means or not. Thus, if the stencil be adapted for coaction with studs upon a bar, as indicated in Fig. 1, the clamping device may be swung backwardly and inwardly toward the axis of the drum, the stencil placed in position over the studs and the clamp swung to operative position when it will overlie and protect the advancing forward edge of the stencil which is commonly subjected to excessive wear. On the other hand, if such stencil be unprovided with special means of attachment, as, for instance, the perforations designed to coact with studs or projections upon a cross-bar, the forward edge of the same may, as above indicated, be turned inwardly over the forward pad-holding rod F or other suitable part of the drum, and the clamping device operated as above described to secure such forward edge in position.

Preferably, means will be employed for locking the clamp in operative position, in order to prevent detachment thereof, as, for instance, by the jar of the machine. In the drawing, I have shown the main or body portion of the clamp as provided with a spring having downwardly turned forward end, so arranged as to coact with such a projection-carrying bar as that above indicated. In operation, when the clamp is pressed to operative position, such spring will take under said bar, requiring pressure of the hand to lift the clamp to free the stencil from the machine. Of course, if such a projection-carrying bar be not employed, a spring or springs may still be carried by the clamping device, and this or these may coact with pins or projections carried upon the inner surface of the drum heads A, B. Such a modification of the mechanism illustrated in the drawing is obvious and does not, therefore, require illustration.

35 While I prefer, upon practical considerations, to employ the clamping device in coaction with the forward pad-carrying rod as hereinabove described, I do not

desire to be understood as limiting the invention thereto. If such a rod be not employed, the clamp may coact with any other device holding the pad in position, or if the pad do not extend over the end of the stencil-carrier (or such a bar as may be employed to bound the edge of such stencil-carrier), then such clamping device may coact with the end of said carrier or such a bar, the forward edge of the stencil being turned over the same, in order to permit it to be clamped in position, as hereinabove described.

Having now described my invention, what I claim as new therein and desire to secure by Letters Patent is as follows:—

1. In a stencil-printing machine, the combination with a drum, of a part moving with said drum and affording means for attachment of the forward end of a stencil-sheet, a device adjacent to said part, and mechanism in juxtaposition to said part and adapted to coact with said device to secure the end of the stencil-sheet in position on said drum, substantially as set forth.

2. In a stencil-printing machine, the combination with a drum, of a part moving with said drum and having projections for coaction with the forward end of a stencil-sheet, and a movable securing device adjacent to said part and moving with said drum, said device being adapted to secure the forward end of a stencil-sheet in position, substantially as set forth.

3. In a stencil-printing machine, the combination with a drum, of a part moving with said drum and affording means for attachment of the forward end of a stencil-sheet, a supporting member carried by said drum rearward of said part, and a movable securing device carried by the drum forward of said part and adapted to coact with said member to secure the forward end of the stencil-sheet in position on the drum, substantially as set forth.

This specification signed and witnessed this 28 day of December 1903.

ALBERT B. DICK.
